VIRGIL E. TROUANT, OF WILKINSBURG, PENNSYLVANIA, ASSIGNOR TO WESTINGHOUSE ELECTRIC & MANUFACTURING COMPANY, A CORPORATION OF PENNSYLVANIA

SYSTEM OF TELEVISION

Application filed February 5, 1929. Serial No. 337,589.

My invention relates to methods of employing radio-frequency currents in the transmission and reproduction of pictures and sounds.

5 One of the objects of my invention is to provide a system which shall enable a modulated electrical quantity of small power fluctuating many thousand times per second to generate a luminous flux of high intensity 10 which shall faithfully reproduce said modulations.

Another object of my invention is to provide an efficient system by which an ordinary modulated broadcast wave may generate a 15 luminous flux of high intensity which shall faithfully reproduce said modulations, and shall operate in doing so with a high luminous efficiency.

Another object of my invention is to provide 20 a method by which a modulated non-electrical quantity of small power may generate a luminous flux of high intensity, which shall faithfully reproduce the modulations of said non-electrical quantity.

25 A further object of my invention is to provide a system adapted to transform the energy of ordinary broadcast waves into light of high luminous efficiency and without the necessity of transmutation to other frequencies than 30 those of the broadcast band.

Substantially all the present systems of transmitting pictures to a distance, and of recording sound through photographic agencies, produce their effects by modulating an 35 electric current of relatively small power in accordance with a non-electrical quantity which it is desired to reproduce and cause this electric current to control a light flux as nearly as possible proportional in instantaneous magnitude to the fluctuations of the modulated electric current aforesaid. Since the light flux must, accordingly, fluctuate at a frequency of many thousands per second, it is practically necessary that it shall comprise 40 a gaseous discharge device, such devices being the only light source capable of varying in intensity with such extreme rapidity. Ordinary glow discharges have, however, certain undesirable qualities: first, they are of relatively low intrinsic brilliancy and, second, there is

a voltage drop at the cathode which is many times the voltage drop in the luminous column of the discharge. It is a consequence of the first of these defects that in order to obtain a sufficient total amount of light, the luminous source must be of very large dimensions; and it is a consequence of the second of these defects that in discharge tubes of any practicable size, almost the entire energy goes to overheat the cathode and only a very small 55 remnant actually produces useful light. On the other hand it is highly desirable for many reasons that the light flux employed in systems of the types under discussion shall come from a relatively small source of high intrinsic brilliancy and high luminous efficiency. The present low intensity glow discharge devices of large size and poor efficiency are, therefore, highly unsatisfactory. 60

It is also a characteristic of the television and photophone systems recently developed that they must take a modulated control quantity of relatively small power and faithfully amplify it before it can be employed to modulate the light flux which they ultimately produce. In order that the amplified quantity shall be a faithful reproduction of the original, it is necessary that all components, whatever their frequency, present in the original shall be amplified in equal degree. 70 It is practically impossible, however, to devise an amplifying system which shall magnify in equal degree all the components of the non-electrical quantity which it is desired to reproduce. Amplifier systems can be made 75 which will amplify in substantially equal degree component currents of all frequencies comprehended within a considerable band above and below some predetermined base frequency; that is to say, an amplifier can be designed which will amplify in substantially equal degree currents of all frequencies between limits of say, 50 kilocycles above and 50 kilocycles below a base frequency of 1,000 kilocycles. A band of frequencies 100,000 cycles wide is accordingly faithfully amplified by such an arrangement; whereas, it would be impossible to design an amplifier 85 capable of magnifying in equal degree currents of all frequencies between zero and 100 90 kilocycles. 95

100

kilocycles, although as will be noted the total range of the frequency "band" is no greater in the latter case than in the former.

In accordance with the well known principles of alternating current theory, if the amplitude of an alternating current of 1,000 kilocycles per second is modulated at a frequency between zero and 100 kilocycles per second, the resulting current can be resolved into two component currents, one having a frequency lying within the band between 900 and 1,000 kilocycles per second, and the other having a frequency lying within the band between 1,000 and 1,100 kilocycles per second.

Since, as has been explained above, an amplifier can be designed which will faithfully amplify currents throughout such a band of frequency as has been last mentioned, it may be taken as a practical requirement that, if a control quantity undergoing modulations up to 100 kilocycles per second is to be amplified, it shall first be combined as has just been described, with a carrier frequency of the order of 1,000 kilocycles per second and shall then be put through an amplifier designed to transmit a band of frequencies 100 kilocycles wide in the neighborhood of the latter figure. It can, accordingly, be taken to be a consequence of the foregoing facts that there will be available for producing the desired light flux in a photo-electric system of the sort to which my invention is applicable, a modulated alternating current of a frequency lying within the ordinary radio broadcast range.

The facts outlined above thus lay down certain requirements which it would be decidedly advantageous if the luminous source to be controlled by a television or photophone system could fulfill; namely, it must be adapted for direct energization by currents of broadcast frequency and must respond instantaneously and with substantial proportionality to the modulated fluctuations of the latter; for space economy, since space is ordinarily at an extremely high premium in such apparatus, the light flux should be generated at a high luminous efficiency; and the light source itself should preferably be of high intrinsic brilliancy. As has been pointed out, the glow discharge tubes now employed signally fail to meet the foregoing conditions; but it will be seen that the arrangement which I am about to describe fulfills them very completely, and that the inherent properties of the various components of the resulting arrangement so fit them to conjoint operation that they constitute a combination which produces results not attainable with arrangements hitherto employed.

In accordance with my invention I employ as the luminous source of my systems a discharge tube enclosing gas at low pressure; and instead of providing it with the con-

ventional electrodes for conduction of current to said gas, I excite the tube to luminosity solely by the inductive effect of a winding carrying the high frequency modulated output of the amplifier system of the general character above described. It is essential, if luminosity is to be excited in the foregoing manner, that the inducing current shall be of extremely high frequency; and currents of the frequency ideal for amplification in accordance with the principles described above are also ideal for thus exciting luminosity. Furthermore, the luminous intensity of such a discharge tube follows instantaneously and faithfully the fluctuations of the amplifier output current. It has an intrinsic brilliancy many times that which can be produced without sputtering of the electrodes in any tube now known; and since the entire electrical energy goes into the excitation of luminosity in the gas and none is lost in voltage drop at an electrode surface, the electrical efficiency is many times higher than the conventional tube of the present art. Such a tube is accordingly adapted to fulfill completely the conditions imposed by the electrical characteristics of the apparatus which must be employed to control the luminous discharge, and is adapted to employ directly and without the necessity of any intermediate transformation the electrical output of such an amplifier system as is practically an indispensable component of arrangements of the character under discussion.

With the foregoing principles and objects of my invention in mind, the latter will be more fully understood upon reading the following specification taken in connection with the drawings, in which;

Figure 1 shows a photophone system embodying my invention and adapted to photographically record speech or music on a moving film in a manner well known in the art, and

Fig. 2 shows a television receiving system constructed in accordance with my invention.

Referring in detail to Fig. 1, a telephone transmitter 1 of conventional form controls the grid potential of a three-electrode amplifier tube 2 in a manner too well known to require further description here. A three-electrode tube 3 is provided with circuit connections of a well known type adapted to cause it to produce high frequency electrical oscillations. Assuming that sounds of frequency up to, say, 20 kilocycles per second, are impressed upon the microphone 1, the grid of tube 2 is caused to fluctuate in potential relative to the cathode at a corresponding frequency. As is well known, in the radio art, the plate current of the tube fluctuates at the same frequency but with a greater power intensity.

The oscillator tube 3 may be adjusted by means of the variable condenser 4 to generate oscillations of a frequency of the order of, say 1,000 kilocycles per second. The flow of plate current to the tube 2 will cause a modulation of the high frequency currents generated by the tube 3, such modulation being at the frequency of the sounds impressed upon the microphone 1. Under the conditions just described, the current in the primary winding of the output transformer 5 may be considered to be made up of two currents in addition to the unmodulated carrier current, one falling in a frequency band between 1,000 and 1,020 kilocycles per second and the other falling within a frequency band between 980 and 1,000 kilocycles per second.

The secondary of the output transformer 5 may be connected as the input element of an amplifier comprising three-electrode tubes 6 and 7 of conventional form. The variable condensers 8 and 9 in the grid circuits of tubes 6 and 7 may be adjusted to permit the transmission of the input band 980 to 1,000 kilocycles derived from transformer 5. While the amplifier system has been described as a transformer coupled, it will be recognized that any suitable amplifier arrangement known in the art may be employed; and that the number of stages may be varied to suit actual operating conditions met in any particular case.

The output circuit of tube 7 contains the variable condenser 10 and a coil 11 in shunt thereto and this local circuit may be tuned to the same frequency as the input circuits of the amplifier. The coil 11 is placed in good inductive relation to an enclosing bulb 12 which may be of glass, exhausted by methods well known in the art and provided with an atmosphere of gas at a suitable pressure. For instance, I have found a spherical bulb four inches in diameter enclosing neon at a pressure of one millimeters mercury to be suitable for many purposes, and to operate satisfactorily when the coil 11 is of 70 ampere turns at a frequency of 4,800 kilocycles per second. The bulb 12 preferably contains no metallic electrodes. Other gases that may be employed are argon, helium and mercury vapor.

It will be found that the modulated high frequency current circulating in the winding 11 induces a glow discharge of high intrinsic brilliancy in the bulb 12 and that this discharge varies in instantaneous and faithful response to the modulation of the current in winding 11 consequent upon the variations in the output current from telephone transmitter 1.

While numerous optical systems in which the light flux from the bulb 12 may be employed will be evident to those skilled in the art, Figure 1 shows as a specific example a diaphragm 13 having a central opening which

transmits light through the lens 14 on to a slit 15 in a screen 16. Immediately behind the slit 15 is positioned a moving film 17 mounted in a manner well known in the photophone art. As the film 17 moves past the slit 15, the fluctuations in intensity of the light from bulb 12 are recorded photographically; and after subsequent development, the film 17 may be employed to reproduce the sounds which were incident on transmitter 1 by means of systems well known in the photophone art.

It will be recognized that the precise method of employing the light flux from bulb 12 may be varied and that it may be used for many other purposes than photographically recording and reproducing sound, as briefly outlined here.

As another illustration of a system employing my invention, Fig. 2 shows an antenna 21, which impresses upon a hot cathode amplifier tube 22, a received broadcast wave which may be the output of a television picture transmitter. The tube 22 may conveniently comprise a uni-potential cathode 23 maintained at operating temperature by a heater filament 24 and its anode 25 may be enclosed in a screen grid 26 in a manner well known in the radio tube art. The fluctuations in potential of grid 27, resulting from the input signal to antenna 21, are amplified by tube 22 and produce a current in the primary of transformer 28 which varies in accordance with such incoming signal. As a specific example, the incoming signal to antenna 1 may fluctuate with a periodicity of the order of 1,000 kilocycles a second.

It will be recognized that if the incoming signal to antenna 21 is not of a frequency adapted for an efficient or simple amplifier system, it may be changed in frequency by the employment of detectors or heterodyne systems embodying local sources of oscillations, in manners well known in the radio art. Thus piezo-electric crystals may be employed to cause tube 22 to generate a local frequency subject to the modulation of grid 27.

Under the conditions above described, the current in the primary of transformer 28 will have a frequency suited to simple and efficient amplification and such frequency will be such as to most efficiently generate light in a bulb of the type of that described in connection with Fig. 1. The input circuits of amplifier tubes 31 and 32, which may, if desired, be of the same form as tube 22, may be tuned by means of variable condensers 33 and 34 to respond with substantial fidelity to currents of such frequency. The output of transformer 28 will accordingly be amplified through tubes 31 and 32 and appear as a modulated current of a frequency near 1,000 kilocycles per second in the local circuit comprising variable condenser 35 and coil 36, in the output circuit of tube 32. Coil 36 is

- placed in inductive relation to an electrode-
less bulb 37 of the same character as bulb 12
previously described. If desired, a pair of
polished reflectors 38 and 39 may be posi-
5 tioned adjacent the bulb 37. The reflectors
38 and 39 may be connected to constitute an
additional capacity in shunt to variable con-
denser 35 and they will induce a fluctuating
10 electric field through the gaseous atmosphere
in bulb 37.
- In the foregoing arrangement it will be
readily evident that modulated high-fre-
quency currents in coil 36 and, if used, the
15 potential impressed on reflectors 38, 39 will
produce a light flux in bulb 37, which will
be modulated in substantial fidelity to the
incoming broadcast waves incident upon an-
tenna 21. The light emanating from bulb
20 37 may be employed in numerous ways; for
example, a rotating disc 41 provided with a
series of spirally disposed holes may be
rotated in front of bulb 37 at a frequency
synchronized by well known methods with
25 that of a similar disc in the television trans-
mitter. Anyone viewing the light of bulb
37 through the rapidly rotating holes in disc
41 will see a reproduction of the picture being
transmitted from the television sending station.
- 30 It will be recognized that other specific
arrangements for utilizing the light flux of
bulb 37 for television reception or other pur-
poses may be employed. Such arrangements
are well known in the television art and their
35 applicability in connection with applicant's
invention will be readily evident. It will
also be recognized that numerous accessory
arrangements, such as filters and other de-
vices for suppressing undesired side bands
40 and harmonics, and for maintaining a tele-
vision receiving optical system in synchronism
with that of the television sending station,
may be employed in connection with my
invention without departing from, or in
45 many cases without in any way modifying,
the principles thereof. It will also be evi-
dent that other forms of amplifiers than those
specifically described here may be employed
for that element of my arrangement.
- 50 While the coils 36 provide the preferable
method of exciting discharge in bulb 37, it
will be recognized that it may be desirable
in certain instances to employ the plates 38
and 39 alone for such a purpose, the coils 36
55 being then removed to a distance and merely
playing the part of a tuning inductance in
the output circuit of the amplifier. It is
also within the purview of my invention to
provide the bulb 37 with auxiliary electrodes
60 to supplement the purely inductive actions of
coils 36 or blades 38 and 39. However, it is
my present belief that the purely inductive
arrangement shown in the drawings will be
found preferable for most purposes. It is
65 also within the purview of my invention to

transform the frequency of the current being
amplified at other stages of the amplifier
than the first as here described. In some
instances, it will of course be unnecessary
and undesirable to employ an amplifier of
70 the original input power; but even in such
cases it will usually result in more effective
operation if the exciting current of bulbs 12
and 36 is given a frequency of the order of
75 1,000 kilocycles. Fig. 1 embodies one sys-
tem for transforming an input of power fre-
quency into a modulated current of such
frequency; and other methods are well
known.

It is a valuable property of the inductively
excited light source having the dimensions
and structure already given as a specific ex-
ample that the light generated seems to be
much more exactly proportional at any time
80 to the instantaneous current output from the
amplifier than is the case with the conductively
excited light sources of the present art,
and believe this property, which is of the
greatest practical value, to be characteristic
85 of other atmospheres and dimensions also.
The light flux can be arranged to be quite
strictly proportional at all times to the in-
stantaneous magnitude of the current in the
inducing coil.

90 Many modifications of the principle of my
invention will be evident to those skilled in
the art and it is by no means limited to the
specific embodiments here disclosed. I ac-
cordingly desire that the claims be given a
95 broader interpretation, of which their terms
are reasonably susceptible, taking into con-
sideration the limitations as imposed by the
prior art.

99 I claim as my invention:

1. In combination with an input circuit
105 energized by a modulated carrier current, an
evacuated envelope containing a gas at re-
duced pressure, means for subjecting said
envelope to the inductive influence of said
modulated carrier current, and means for
110 scanning said envelope.

2. In combination with an input circuit
115 energized by a modulated carrier current, an
evacuated spherical envelope containing a gas
at reduced pressure, means for subjecting
said envelope to the inductive influence of
said modulated carrier current, and means for
120 scanning said envelope.

In testimony whereof, I have hereunto sub-
scribed my name this 31st day of January,
1929.

VIRGIL E. TROUANT.
